(57) **CLAIM**

The ornamental design for a removable cover for a knot of a tie, as shown and described.

DESCRIPTION

FIG. 1 is a perspective view of the removable cover for a knot of a tie showing our new design;

FIG. 2 is a bottom plan view thereof;

FIG. 3 is a top plan view thereof;

FIG. 4 is a left side view thereof;

FIG. 5 is a right side view thereof;

FIG. 6 is a front view thereof; and,

FIG. 7 is a perspective view of the removable cover for a knot of a tie shown in an example environment.

The portions of the shirt outlined by broken lines in the view of FIG. 7 illustrates the environment of the claimed design and forms no part of the claimed design.
